(57) **CLAIM**

The ornamental design for a wireless charger, as shown and described.

DESCRIPTION

FIG. 1 is a perspective view of a wireless charger showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a right side view thereof, shown in a usage state.

FIG. 9 is an enlarged front view thereof, shown in a usage state.

FIG. 10 is a rear view thereof, shown in a usage state.

FIG. 11 is a left side view thereof, shown in a usage state.

FIG. 12 is an enlarged detail view of area 12 shown in FIG. 1; and,

FIG. 13 is an enlarged detail view of area 13 shown in FIG. 1.

The broken lines in the drawings depict portions of the

wireless charger that form no part of the claimed design.
